UNITED STATES PATENT OFFICE.

ALFRED M. STOFFLET, OF MAUCH CHUNK, PENNSYLVANIA.

DISPLAY-EASEL.

No. 880,049.

Specification of Letters Patent.

Patented Feb. 25, 1908.

Application filed June 24, 1907. Serial No. 380,610.

To all whom it may concern:

Be it known that I, ALFRED M. STOFFLET, a citizen of the United States, residing at Mauch Chunk, in the county of Carbon and State of Pennsylvania, have invented a new and useful Improvement in a Display-Easel, of which the following is a specification.

This invention relates to display easels for displaying articles of merchandise, the object being to provide an easel so constructed that a cake of soap or package of starch, or cereal can be readily placed therein.

Another object of my invention is to provide an easel with a support so that it will be held in an inclined position, the support also supporting the article.

Another object of my invention is to provide an easel in which a support can be formed of card-board or metal and one which is provided with opposite disposed flaps for supporting the article.

With these objects in view, the invention consists in the novel features of construction, combination and arrangement of parts, hereinafter fully described and pointed out in the claims.

In the drawing forming a part of this specification:—Fig. 1 is a perspective view of my improved easel. Fig. 2 is a vertical sectional view through the same. Fig. 3 is a rear view of the easel. Fig. 4 is a perspective view of a modified form partly broken away.

Referring to the drawing A indicates the body portion of my improved easel which is preferably formed of card-board, and is adapted to have advertising matter thereon. Secured to the back of the body is the flanged edge B' of a triangular shaped support B which holds the body in a slightly inclined position. An opening A' of any desirable shape, is formed in the body of the easel and the support which is preferably formed of tin, is split from the flanged edge inwardly in alinement with the upper and lower edge of the opening. The tongue formed by the split is split centrally and the flaps C are bent outwardly in opposite directions, forming backs for the article which is placed in the opening, and rests on the lower edge of the

split of the support. It will be seen that when an article such as a cake of soap or a box of starch is placed in the opening, it will project out beyond the face of the easel and be securely held therein without any danger of it falling out, it of course being understood, that the distance between the flaps of the support and the face of the body is less than the thickness of the article to be displayed.

In the modification shown in Fig. 4, I show an easel D formed all of paste-board, the support being grooved along its line of connection to the body, so that it can be readily folded flat upon the body, so as to readily allow the same to be shipped in an envelop. In this form the tongues on the support are done away with, the rear edge of the support formed by the notch serving for a stop for the article, when arranged in the opening.

From the foregoing description, it will be readily seen that I provide a very novel easel which is exceptionally cheap and simple in construction, and one which will hold an article securely in place, so that it can be readily seen.

Having thus fully described my invention, what I claim as new and desire to secure by Letters Patent is:—

1. A device of the kind described, comprising a body having an opening formed therein a triangular support secured to the rear of said body having a notch registering with said opening, and flaps extending in opposite directions from the rear of said notch forming a back for an article when arranged in the opening of the body.

2. In a device of the kind described, the combination with a body provided with an opening, of a flanged triangular shaped support secured to the rear of the body provided with a notch, the upper and lower edges of which are in alinement with the upper and lower edges of the body, and flaps extending in opposite directions from the rear of the notch forming a back.

ALFRED M. STOFFLET.
